UNITED STATES PATENT OFFICE.

ISAAC BARNETT, OF NEW YORK, N. Y.

COMBINATION PINNING AND RIVETING MACHINE.

1,235,873.

Specification of Letters Patent.

Patented Aug. 7, 1917.

Application filed July 11, 1916. Serial No. 108,584.

To all whom it may concern:

Be it known that I, ISAAC BARNETT, a citizen of the United States, residing in the city of New York, borough of Manhattan, county 5 and State of New York, have invented a certain new and useful Combination Pinning and Riveting Machine, of which the following is a specification.

This invention is a pinning and riveting machine and is adapted, more particularly, 10 for the riveting together of the parts of pocketbook and handbag frames for the purpose of securing the leather or fabric body of the pocketbook to the metallic frame 15 thereof.

One of the objects of the invention is to provide a machine which will automatically feed the rivets to a riveting point, place them in a position for insertion into previously 20 formed holes in the pocketbook frame, cut off the rivets to the desired length, and subsequently head them over to secure the part of the frame together, with the wall of the pocketbook therebetween.

25 A further object of the invention is the provision of mechanism which will carry out the above enumerated operations in a continuous, consecutive manner so that the machine will operate with efficiency and expeditious, whereby the operations of inserting a rivet, cutting it off, and heading it over may be accomplished rapidly, and no appreciable period of dwell need occur between successive riveting operations.

35 Speaking generally, the invention embodies mechanism for feeding rivets, one at a time, to a riveting point, mechanism for holding the rivet in operative position at the riveting point, means for holding the rivet 40 in riveting position and in place in the article operated upon, means for cutting off the rivet to the desired length, and means for heading over the rivet.

In the preferred practical embodiment of 45 the invention, the various mechanisms are operable from a common prime mover and are connected together so that they operate in logical sequence for the accomplishment of the work to be done.

50 Features of the invention, other than those specified, will be apparent from the herein-after detailed description taken in conjunction with the accompanying drawings.

In the accompanying drawings I have illustrated one practical embodiment of the 55 invention, but the construction shown therein is to be understood as illustrative, only, and not as defining the limits of the invention.

Figure 1 is a front elevation of a machine 60 embodying the present invention, portions of the machine being shown in section in the interest of clearness.

Fig. 2 is a back elevation of the machine 65 shown in Fig. 1.

Fig. 3 is a section taken on line 3—3 of Fig. 1.

Fig. 4 is a section taken on line 4—4 of Fig. 3, certain parts being omitted in the interest of clearness.

Fig. 5 is a section taken on line 5—5 of Fig. 1.

Fig. 6 is a detail side elevation of a certain cam member which is preferably employed for controlling the rivet cut-off mechanism.

Fig. 7 is a section on line 7—7 of Fig. 6, showing the contour of said cam member.

Fig. 8 is a section taken on line 8—8 of Fig. 1, showing the mechanism, including a 80 delivery gate, for delivering the rivets, one by one, to the riveting point.

Fig. 9 is a detail elevation, partly in section, of the delivery gate shown in Fig. 8. The delivery gate of Fig. 9 is shown as 85 viewed from the face thereof adjacent the center of a hopper or magazine adapted to contain the rivets.

Fig. 10 is a view similar to that of Fig. 9, but viewing the gate from the opposite 90 side, and

Fig. 11 is an underneath plan view of said gate.

Referring to the drawings, A designates a frame or standard upon which the operating parts of the machine are mounted. Standard A is in the form of an upstanding wall or web provided at its lower end with a suitable base A' of sufficient width to furnish a stable mounting for the machine 100 when the same is secured to a fixed support.

Secured to, or formed integral with, the front face of standard A, is a rivet-holding block B. This block is provided with a horizontal, cut-away portion b, in which 105 are pivotally secured two complementary

clamping jaws C, pivoted at c' , as clearly shown in Figs. 1 and 3. A pair of leaf springs c are secured as at c^2 , and their free ends bear against the exterior faces of the 5 two clamping jaws C for the purpose of normally forcing them together. The clamping jaws, as shown in Fig. 3, are cut away back of their noses, to provide a space in which the rivets α are adapted to be deposited, one at a time, through a passage d 10 (see Fig. 4) leading from a hopper or magazine D, whence they are delivered, one at a time, by means hereinafter described, and gravitate into the position shown in dotted 15 lines in Fig. 4.

With rivet-holding block B co-operates means for positioning rivets, deposited as described, so that they may be brought into co-operative relation with the work to be 20 done, and this means is shown in the drawings as embodied in a plunger E, slidably mounted for longitudinal movement in the rivet-holding block, extending rearwardly beyond the same and carrying near its free 25 end an operating head F provided with two fixed collars f . The plunger E is threaded through the operating head F, a lock nut f' being provided to preclude the parts from working loose. A spring G is coiled around 30 the plunger intermediate operating head F and rivet-holding block B, and serves to normally retract the plunger, *i. e.*, to force the operating head away from the rivet-holding block.

Opposed to the operations of spring G is a mechanically controlled bell-crank lever H, the upper end of which is bifurcated to straddle operating head F and lie between the fixed collars f . Bell-crank H is pivoted 40 to frame A, as at h , and is also provided with a roller h' adapted to ride on the face of a cam I fixed on a stub shaft i and suitably journaled in frame A.

It will be noted from Fig. 1 that cam I 45 has three phases, an intermediate phase i' , a low phase i^2 , and a high phase i^3 . When the cam is in the position shown in Fig. 1, with roller h' on the intermediate phase i' of the cam, the plunger is in the intermediate position shown in full lines in Fig. 3. When the cam moves in a clockwise direction, to bring the roller h' upon the low phase i^2 of the cam, spring G retracts plunger E into the dotted line position shown in Fig. 3, 55 wherein its free end is farther away from the noses of clamping jaws C than was initially the case. However, when the cam still farther advances to bring the high phase i^3 under roller h' , bell-crank H is 60 oscillated to such extent as to force the plunger forwardly between the noses of clamping jaws C, so that it extends between and beyond the ends of said clamping jaws, as shown in dash lines in Fig. 3.

It will thus appear that, if a rivet α has

been deposited in the position shown in dotted lines in Fig. 4, while the plunger is in the retracted position which it assumes when roller h' is in contact with the low phase of the cam, on the movement of the cam in a counter-clockwise direction as will be hereinafter described, the finishing counter-clockwise movement of the cam will cause the intermediate phase i' to operate the plunger to the full line position of Fig. 3, for the purpose of forcing the rivet α forward into the full line position of Figs. 3 and 4. The end of the rivet, in such position, will protrude beyond the noses of clamping jaws C. When the cam is subsequently moved in a clockwise direction to bring the high phase i^3 of the cam under roller h' , a forward impulse is imparted to plunger E, which carries the rivet through and beyond the clamping jaws and frees it 85 from said jaws, for reasons hereinafter manifest.

Movement may be imparted to stub shaft i , on which cam I is fixed, in any suitable manner, but, in the preferred form of the invention, said shaft i has affixed thereto an arm j , to the free end of which is pivoted a link J , extending downwardly and into co-operative relation with suitable treadle mechanism. Treadle operating mechanism 95 is so well known that it has not been considered necessary to illustrate the same, as any one of the large number of forms may be employed. Suffice it to say that any mechanism which will serve to draw link J downwardly to oscillate stub shaft i in one direction and, when released, will permit of the oscillation of said shaft in an opposite direction, will satisfactorily actuate the mechanism of this invention.

In the foregoing description, the manner in which rivets, fed to the rivet-holding block, are automatically moved to a riveting position, has been specifically described, and mechanism will now be set forth whereby 110 excess length of rivet may be cut off and the remaining portion of the rivet subsequently headed over. It will be understood that, in operating the machine of this invention, the rivet is brought, in the manner described, to assume the full line position of Figs. 1, 3 and 4. The parts of the pocket-book which it is desired to rivet together are next manually assembled by the operator so that rivet-holes subsequently formed therein are brought into registration, with the fabric or leather bag portion intermediate the parts of the frame. After the operator has manually assembled these parts as described, he manipulates the same into such 125 position in the machine that the protruding portion of the rivet is passed through the rivet-holes of the frame portions y and bag portion y' , which parts are clearly shown in section in Fig. 2 in the position in which 130

they are placed by the operator. After the parts have thus been positioned, the cutting-off of excess rivet length and the heading-over operation are successively carried out 5 in the manner next to be described.

Fixed on stub shaft i , at the backside of standard A, is a second arm j^2 , to the free end of which is pivoted one end of a link j^3 , the upper end of which is pivoted to one 10 arm of a heading lever K pivoted on a post k , fixed in horizontal position on the standard. When oscillating movement is imparted to stub shaft i , this movement is transmitted through arm j^2 and link j^3 to 15 heading lever K, for the purpose of oscillating the same.

Also mounted for pivotal movement on post k is a hanger L provided with a foot l , on which is mounted a pair of coöperating 20 cutter jaws M, as shown in Figs. 1, 2 and 5. Hanger L is normally impelled in a direction to bring the cutter jaws into engagement with the rivet by means of a spring M', but the tension of spring M' is opposed 25 by a finger l' which is mounted on hanger L and extends upwardly and over the edge of heading lever K. Accordingly, while the spring serves to normally advance hanger L, it cannot move unless lever K is moved. To 30 this extent, therefore, hanger L is under the control of lever K.

Mounted on foot l of hanger L, and secured thereon by a pivot pin m , are the two 35 cutter jaws M, the sharpened edges m' of which are normally forced away from one another by a coiled spring m^2 secured to the other ends of the arms of said jaws. Threaded through each arm of said cutter 40 jaws, and at the other side of pivot pin m from the sharpened edges m' of said jaws, are two set screws m^3 , each of which is provided with a lock nut m^4 . The inner ends of 45 set screws m^3 are preferably rounded over and coöperate with the opposite faces of a cam member N, which is secured at the lower 50 forward end of heading lever K, as clearly shown in Figs. 1 and 5. Spring m^2 forces the power arms of the cutter jaws together, and thereby maintains the set screws at all times in engagement with the opposite faces of said cam member.

Cam member N is shown in detail in Figs. 6 and 7, and in dotted lines in Fig. 5. Said member is of decreased thickness at its forward end n and at its rear end n' , and of greater thickness between its ends, as at n^2 . It will be manifest, therefore, that, when set screws m^3 are near the opposite ends of said cam member, spring m^2 will be 60 allowed to force the power arms of the cutter jaws together and open the jaws. However, when the wider portion n^2 is brought between set screws m^3 , the power arms of the cutter jaws are forced apart against the 65 tension of spring m^2 to close said jaws.

Mounted on the free, forward end of heading lever K, and immediately above cam member N, is an elongated rod O adapted for longitudinal adjustment relative to lever K by means of two jam-nuts o' . 70 Rod O is tapered at its forward end, as at o , and is so positioned on lever K that, when the forward end of said lever is forced forward for the riveting operation, rod O will be brought into substantial alinement with a rivet x held by clamping jaws C. The function of rod O, with its tapered end o , is to serve as a "set" for upsetting or heading-over the rivets, as will be hereinafter described. 75 80

Assuming that a rivet has been positioned in clamping jaws C, and the operator has positioned the pocketbook parts y and y' on the rivet, as shown in Fig. 2, the next operation performed by the machine is to cut off the rivet and subsequently head it over. The normally retracted position of the parts, for bringing about these results, is as shown in Fig. 2. Link J is now depressed by suitable treadle mechanism to 90 oscillate stub shaft i in such direction as to lift link j^3 . This lifting movement of link j^3 will serve to oscillate heading lever K toward the riveting point. It will be noted, however, from an inspection of Figs. 1, 2 95 and 5, that pivoted hanger L moves under the impulse of its spring M' in advance of lever K, and, as these parts move forward as described, the set screws which govern the cutter jaws are in engagement with cam 100 member N near its forward end n , and, accordingly, said clamping jaws are open.

The association of the parts is such, and cam I and arm j^2 are so mounted on stub shaft i , that, as said shaft is rotated to bring the sharpened ends of cutter jaws M into position to straddle the rivet x and press against the adjacent frame member y of the pocketbook, cam I is shifted to the position wherein the high phase i^3 of the cam engages with roller h' at just about the time when the cutter jaws engage with the pocketbook frame. The result of this operation is that plunger E is forced forward between clamping jaws C as hereinbefore described, 110 thereby forcing the rivet through and beyond the clamping jaws and bringing its head against the adjacent face of the pocketbook frame. Moreover, the plunger follows the rivet to the position described so as to 115 form a sort of anvil which, coöperating with the ends of the cutter jaws, tightly compresses the parts to be riveted. The high phase of the cam remains under roller h' during a further rotation of stub shaft i , 120 but said stub shaft further pivotally moves the heading lever K to bring its forward end closer to the riveting point. This results in forcing cam member N forwardly 125 between set screws m^3 of the cutter jaws so 130

that, as the widest portion n^2 passes between said set screws, the sharpened edges m' of the cutter jaws are forced together and cut off the excess, protruding portion of the rivet. As lever K continues to pivotally move, set screws m^3 approach one another by their engagement with the constantly lessening thickness of cam member N and open up the cutter jaws. The rivet having been 10 cut off and the cutter jaws opened, the continued forward movement of the free end of lever K brings the set o into engagement with the end of the rivet, and, as the other end of said rivet is in engagement with the 15 anvil-like end of plunger E, said rivet is upset or headed-over, as will be readily manifest. It will, of course, be understood that the foregoing operations are carried on in a continuous manner and fairly rapidly, so that the set o is brought against the end of the rivet with considerable force, to satisfactorily manipulate the rivet for the purpose of securely fastening the frame sections to the body of the handbag or pocket-book.

At the conclusion of the foregoing operations, the operator releases the pressure on the foot-pedal or other actuating means, whereupon a spring Q exerts a downward 30 pull upon the power arm of heading lever K and swings it back into normal, retracted position, carrying therewith hanger L and placing its spring M' under tension. Upon the retraction of heading lever K and hanger 35 L, the pocketbook is released and may be removed from the machine or manipulated into position for receiving the next rivet.

As heretofore stated, the rivets are automatically fed from hopper or magazine D, 40 and, while the feeding or dispensing means may partake of various forms, one form which operates with efficiency is illustrated and will now be described.

The hopper is shown as of inverted, conical shape, and passing through a substantially central aperture in the base thereof is a slidable rod P which extends downwardly through base A' of the machine, as shown more particularly in Fig. 2. Vertical, reciprocating movement is imparted to this rod by a link p pivoted to the frame, as at p', having a pin and slot connection with rod P. A second link p^2 is pivoted at its opposite ends to arm j of the stub shaft and 50 to link p intermediate the pivot point p' thereof and said pin and slot connection with rod P. When arm j is depressed, links p^2 and p are similarly moved and rod P is lowered into the dotted line position of 55 Fig. 1. On the other hand, when arm j is raised, the operations are reversed and rod P is elevated. A quantity of rivets is adapted to be deposited in hopper D, and the function of rod P is to lift one or more 60 of said rivets at a time and deposit them

in a chute or feed slot, from which they may be delivered, one at a time, to the machine. This feed slot is shown in the form of two plates r which are spaced apart just a sufficient distance to allow the shank 70 of a rivet to extend between them, but to maintain the head of the rivet on their upper edges, as shown in Fig. 8. Two upwardly diverging wings r' are formed along the portion of the upper edges of plates r adjacent 75 rod P so that, as the rivets are lifted by the end of the plunger, they are dumped between wings r' and automatically fall down into the position shown in Fig. 8. The inclination of the upper edge of the plates, 80 as shown in Fig. 1, is at a sufficient angle to cause the rivets to gravitate toward the edge of the hopper, whence they pass off the ends of plates r and fall into the chute or duct d which leads to the riveting point, 85 and which has hereinbefore been referred to.

In order, however, that the rivets may be fed one at a time, a stop-gate or step-by-step advancing mechanism is positioned at the entrance of duct d. This stop-gate is 90 shown in the form of a plate S provided with a stem s, which extends through the wall of hopper D (see Figs. 1 and 8) and thus pivotally mounts the plate. The outer edge of the plate is shaped on the arc of a 95 circle, of which the pin s is the center, and the radius of the plate is such that the lower edge thereof practically touches the upper edges of the rivet-holding plates r. As shown in Figs. 9, 10 and 11, the lower, 100 curved edge of plate S is provided with a channel which has its entrance s' at one face of the plate and its outlet s² at the other face thereof. The inlet to and outlet from the channel are, moreover, out of alignment. 105 When plate S is positioned as described, it normally occupies the upright position shown in Fig. 8, wherein the inlet s' of the channel is positioned at a point removed from the plates r, while the outlet s² 110 is in register with the delivery duct d. It will be manifest that, if, from the position shown, plate S is oscillated in a clockwise direction sufficiently to bring the outlet of the channel into juxtaposition with the head 115 of a rivet x positioned between plates r, the rivet will gravitate into the channel. Moreover, if the plate is then rotated in a counter-clockwise direction back to its initial position, the head of the rivet will be opposite the outlet s² of the channel and will 120 gravitate off the ends of plates r and fall through the delivery duct d. The channel is of such width as to take in but one rivet at a time, so that, when one rivet is in 125 place, the rotation of the plate to deliver the rivet will bring the inner face of the plate against the adjacent rivet and hold it back until the first rivet has been dispensed.

The foregoing oscillating operations of 130

gate S may be automatically carried out in many ways, such, *e. g.*, as by affixing an operating arm t to stem s exterior of the hopper and connecting the free end of said 5 arm, by a link T, to one arm of heading lever K, as shown best in Fig. 2. This connection may, of course, be varied, but, when the specific structure described is employed, the movement of heading lever K to heading 10 over a rivet will simultaneously shift gate S to a position to receive a subsequent rivet and, when the direction of oscillation of lever K is reversed to return it to its normal position, gate S will be oscillated back 15 into normal position and, just before reaching such normal position, the rivet will be released and will fall through discharge duct d. The association of the parts is preferably such that, at about the time 20 when the rivet falls through the discharge duct, the low phase ι^2 of cam I will be beneath roller h' so that plunger E will be withdrawn to such extent as to allow the rivet to fall into a position wherein the movement of the parts to their entirely 25 retracted, normal positions will bring the intermediate phase ι' of cam I under roller h' and force the rivet forwardly into the position shown in Figs. 1 and 3, which is the initial position hereinbefore described. 30

It will be manifest from the foregoing description that the machine of this invention operates successively and automatically to position a rivet to be inserted through holes 35 in a bag frame, force the parts of the bag frame tightly together, cut off the rivet, head the same over, and release the frame subsequently to the riveting operation, the parts thereafter withdrawing to a retracted 40 position to allow of the frame being subsequently positioned on the next rivet. The operations are carried out in rapid sequence and in a thoroughly positive manner. There is no bending or damaging of the rivets or 45 of the bag frame, and the operation of the parts is such as to, in no way whatsoever, subject the operator to injury.

In the foregoing description, the preferred form of the invention has been described, and in this form the machine is 50 operated from any suitable treadle mechanism. Manifestly, however, the machine may be operated in other ways and the structures of the several mechanisms embodied in the machine may be slightly 55 varied without departing from the spirit or scope of this invention, which is to be understood to be as broadly novel as is commensurate with the appended claims.

Throughout the foregoing description, the 60 present invention has been explained as particularly adapted for the riveting together of the frame and body parts of handbags, and pocketbooks. It will be understood, however, that the machine of this invention 65 is not limited to this specific use, as it may

be employed with great efficiency in the making of satchels, suit cases, and other similar structures. In fact, it may be applied for operation in the art generally.

In the preferred method of securing handbag, satchel and pocketbook frames to their bodies, small pins or nails, generally escutcheon pins, are employed as rivets, the sharpened ends of these pins being cut off prior to the riveting operation. These pins 70 or nails have been hereinbefore termed rivets, because they are intended for use as such in the present machine. It will be understood, therefore, that the hereinbefore mention of rivets applies to escutcheon pins, 75 nails, pins, and the like, as the particular style of pin or rivet depends entirely upon the character of the work being done.

Irrespective, however, of the type of rivet employed, or the material operated upon, the 80 present invention provides mechanism for placing the pins or rivets in a position to be readily accessible for operation, thereafter cutting off the superfluous length of the rivet, heading-over said rivet, and finally releasing the work from the machine at the 85 culmination of this cycle of operations. The present invention is, therefore, of marked improvement over such prior art devices as were intended to carry out the riveting operation, only, and dependent on manual manipulation for the carrying out of the other operations in bag construction which the present invention accomplishes in an entirely automatic manner and by a complete 90 cycle of successive mechanical operations. 95

Having thus fully described the invention, what I claim as new, and desire to secure by Letters Patent, is:

1. In a pinning and riveting machine, 105 the combination of a magazine adapted to receive rivets, means for delivering the rivets singly to the riveting point in the machine, means at the riveting point for holding a rivet in a position to receive an 110 article to be operated upon, means for forcing the parts of the article together, means for forcing the rivet free from its holding means, means for cutting off the superfluous length of the rivet, and means for clenching 115 or heading said rivet.

2. In a pinning and riveting machine, the combination of a magazine for holding rivets, clamping jaws for holding a rivet to be operated upon, means for delivering 120 the rivets singly from the magazine to the clamping jaws, means for positioning the rivets in the grip of the clamping jaws, means for cutting off the superfluous length of the rivet, and means for heading-over the 125 rivet.

3. In a pinning and riveting machine, the combination of a magazine for holding rivets, clamping jaws for holding a rivet to be operated upon, means for delivering the 130

rivets singly from the magazine to the clamping jaws, means for positioning the rivets in the grip of the clamping jaws, means for subsequently forcing said rivet free from the clamping jaws, means for cutting off the superfluous length of the rivet, and means for heading-over the rivet.

4. In a pinning and riveting machine, the combination of a magazine for holding 10 rivets, clamping jaws for holding a rivet at the riveting point in the machine, means for delivering the rivets singly from the magazine to the clamping jaws, a pivoted hanger, a pair of cutter jaws pivoted for movement 15 toward and away from one another and mounted on the hanger, pivotally mounted rivet-heading means, and means mounted adjacent the rivet-heading means and adapted to coöperate with the cutter jaws for actuating the latter.

5. In a pinning and riveting machine, the combination of a magazine for holding rivets, clamping jaws for holding a rivet at the riveting point in the machine, means for 25 delivering the rivets singly from the magazine to the clamping jaws, a pivoted hanger, a pair of cutter jaws pivoted for movement toward and away from one another and mounted on the hanger, means for normally 30 impelling the cutter jaws to a position to engage a rivet held by the clamping jaws, pivotally mounted rivet - heading means, means for positively forcing the rivet-heading means into engagement with a rivet held 35 by the clamping jaws, and means mounted adjacent the rivet-heading means and adapted to coöperate with the cutter jaws for actuating the latter, said pivoted hanger being governed in its movements by the operations 40 of the heading means.

6. In a pinning and riveting machine, the combination of means for forcing a rivet through the work to be operated upon, means for cutting off the superfluous length 45 of the rivet, and means for heading-over the rivet.

7. In a pinning and riveting machine, the combination of a frame, mechanism mounted on the frame for holding a rivet in rigid 50 position, means for forcing the rivet through the work to be operated on, means for cutting off the superfluous length of the rivet, and means for heading-over the rivet.

8. In a pinning and riveting machine, the 55 combination of a frame, mechanism mounted on the frame for holding a rivet in rigid position, means for forcing the rivet through the work to be operated on, a cutter member pivotally mounted on the frame, means for 60 moving said cutter member to a position to cut off the superfluous length of the rivet, rivet-heading means also pivoted on the frame and movable to a position to head-over the rivet, and means coöperating with 65 the heading means whereby the movement

of said heading means into riveting position automatically actuates the cutter member to cut off the rivet and immediately thereafter removes the cutter member to a position out of the path of the heading means.

9. In a pinning and riveting machine, the combination of a frame, mechanism mounted on the frame for holding a rivet in rigid position, means for forcing the rivet through the work to be operated on, a cutter member 70 pivotally mounted on the frame, a spring for moving said cutter member to a position to cut off the superfluous length of the rivet, rivet-heading means also pivoted on the frame and movable to a position to head-over the rivet, means coöperating with the heading means whereby the movement of said heading means into riveting position automatically actuates the cutter member to cut off the rivet and immediately thereafter 75 removes the cutter member to a position out of the path of the heading means, means for positively moving the heading means toward and away from the riveting point, and connections between the cutter member and the heading means whereby the pivotal movement of the former is dependent upon the 80 operations of the latter.

10. In a pinning and riveting machine, the combination of means for holding a rivet 95 at the riveting point, a pair of normally open cutter jaws, means for moving the cutter jaws into coöoperative relation to the rivet, and pivotally movable means for forcing the cutter jaws together to cut off 100 the rivet to the desired length.

11. In a pinning and riveting machine, the combination of means for holding a rivet at the riveting point, a pair of normally open cutter jaws, means for moving 105 the cutter jaws into coöoperative relation to the rivet, pivotally movable means for forcing the cutter jaws together to cut off the rivet to the desired length, and means for subsequently heading-over the rivet.

12. In a pinning and riveting machine, the combination of a magazine adapted to contain rivets, a pair of clamping jaws, means for delivering the rivets singly to a position adjacent the clamping jaws, means 115 for forcing a rivet into the grip of the clamping jaws and subsequently forcing it free from the grip of said jaws, and means for heading-over the rivet after the same has been forced free from the grip of the 120 clamping jaws.

13. In a pinning and riveting machine, the combination of a magazine adapted to contain rivets, a pair of clamping jaws, means for delivering the rivets singly to a 125 position adjacent the clamping jaws, means for forcing a rivet into the grip of the clamping jaws and subsequently forcing it free from the grip of said jaws, means for heading-over the rivet after the same has 130

been forced free from the grip of the clamping jaws, and a cam for operating the rivet-forcing means.

14. In a pinning and riveting machine, 5 the combination of a magazine adapted to contain rivets, a pair of clamping jaws, means for delivering the rivets singly to a position adjacent the clamping jaws, a plunger for forcing a rivet into the grip of 10 the clamping jaws and subsequently forcing it free from the grip of said jaws, means for heading-over the rivet after the same has been forced free from the grip of the clamping jaws, and a cam for actuating said 15 plunger.

15. In a pinning and riveting machine, the combination of a pair of coöperating clamping jaws, a magazine adapted to contain rivets, means for delivering the rivets 20 singly from the magazine to a point adjacent the clamping jaws, a spring-retracted plunger adjacent the clamping jaws, means for imparting step-by-step movement to the plunger against the tension of the spring to 25 force a rivet into the grip of the clamping jaws and subsequently forcing it free from the grip of said jaws, means for cutting off the rivet to proper length, and means for heading-over the rivet after it has been 30 forced free from the clamping jaws.

16. In a pinning and riveting machine, the combination of a magazine for containing rivets, means for delivering said rivets singly to a riveting point, means for holding 35 a rivet at the riveting point in a position to receive the article to be operated on, a pivoted lever, a set mounted on the pivoted lever for clenching the rivet, means for moving the set toward and away from the 40 rivet, a pivoted bracket mounted for concentric movement with the lever, a pair of cutter jaws, a spring for normally main-

taining the cutter jaws open, means for impelling the bracket into a position wherein the cutter jaws embrace the rivet held at the 45 riveting point, a stop formed on the bracket and cooperating with the lever to render the bracket responsive in its operations to the operations of the lever, and means mounted on the lever and operable upon the cutter 50 jaws, when the same are positioned to operate upon the rivet, to force the jaws together to cut off the rivet to proper length and subsequently open said jaws to allow of the passage therethrough of the set to head-over the rivet. 55

17. A pinning and riveting machine embodying a magazine adapted to contain rivets, clamping jaws, a discharge chute from the magazine, a gate for limiting the 60 passage of rivets through the chute to one at a time, means for conveying the rivets thus discharged to the clamping jaws, means for forcing said rivets into and subsequently out of the grip of the clamping jaws, and 65 means for heading-over or clenching the rivets.

18. A pinning and riveting machine embodying a magazine adapted to contain rivets, a discharge chute from the magazine, 70 means for bringing the rivets in the magazine into position on the chute, a gate for limiting the passage of rivets through the chute to one at a time, clamping jaws, means for conveying the rivets after being discharged through the gate to the clamping jaws, means for forcing said rivets into and subsequently out of the grip of the clamping jaws, means for cutting off the rivets to the desired length, and means for heading-over or clenching the rivets. 75 80

In testimony whereof I have signed my name to this specification.

ISAAC BARNETT.
